UNITED STATES PATENT OFFICE

144,407

DESIGN FOR A PICTURE VIEWER

Clarence S. McClellan, Santa Monica, Calif.

Application October 10, 1945, Serial No. 122,733

Term of patent 7 years

(Cl. D61—1)

To all whom it may concern:

Be it known that I, Clarence S. McClellan, a citizen of the United States, residing at Santa Monica, in the county of Los Angeles and State of California, have invented a new, original, and ornamental Design for a Picture Viewer, of which the following is a specification, reference being had to the accompanying drawing, forming part thereof, and wherein:

Fig. 1 is a rear perspective view of a picture viewer illustrating my new design;

Fig. 2 is a front view of said viewer;
Fig. 3 is a top plan view of said viewer;
Fig. 4 is a rear view of said viewer; and
Fig. 5 is a side view of said viewer.

I claim:

The ornamental design for a picture viewer, as shown.

CLARENCE S. McCLELLAN.
